UNITED STATES PATENT OFFICE.

FREDERICK KOHNLE, OF DAYTON, OHIO.

INKING DEVICE FOR TICKETING-MACHINES.

1,171,730.

Specification of Letters Patent. Patented Feb. 15, 1916.

Application filed June 17, 1914. Serial No. 845,726.

To all whom it may concern:

Be it known that I, FREDERICK KOHNLE, a citizen of the United States, and residing at Dayton, in the county of Montgomery and 5 State of Ohio, have invented a new and useful Inking Device for Ticketing-Machines, of which the following specification is a full disclosure.

My invention relates to inking mechanism 10 for ticketing or marking machines.

An object of the invention is to unitarily combine the inking devices with the printing devices to form a self-contained printing press, movable toward and from the impression platen.

Another object of my invention is to connect an inking pad upon an oscillating member through the medium of a yielding floating knuckle, for yieldingly compressing the pad against the printing surface and in approximately a parallel plane therewith, and to provide means for rocking said oscillating member at predetermined intervals.

Various other objects of my invention will 25 be more fully revealed from the annexed drawings and description thereof, illustrating a preferred embodiment, and in such drawings like characters of reference denote corresponding parts throughout the several 30 views of which:—

Figure 1 is a right side elevation of my improved ticketing machine, illustrating the inking devices, forming the basis of this invention connected therewith. Fig. 2 is a left 35 side elevation of the upper portion of the machine. Fig. 3 is a right side elevation of the upper portion of the machine with some of the parts omitted for the sake of clearness, and with part of the frame work 40 in section. Fig. 4 is an enlarged mutilated sectional view of the end of the lever arm supporting the inking-pad.

The machine to which the inking devices are applied is made the subject-matter of 45 several applications, among which is an application filed on even date herewith, Serial No. 845724, for printing mechanism, with which the inking mechanism herein conjunctively operates as a preferred construction. The inking devices, however, are not 50 limited in use to such specific type of machine. From the disclosure herein the machine comprises a supporting frame or pedestal 1, an actuator 2 mounted to reciprocate 55 within said frame, which receives its motion from a motor 3 or other power devices con-

nected with the actuator by a pitman 4. A table 5 projects laterally from the frame 1, upon which the material is fed beneath the printing devices, in this instance, that of 60 gang tag strips. The actuator at its exposed extremity has a lateral projecting arm 6, upon which the type-holder 7 is removably, dependently supported. The printing devices, therefore, are unitarily combined with 65 the actuator to move to and from the table 5, making an impression with each downward stroke of the actuator.

As the tag strips are automatically fed and the machine power driven, the devices 70 are constructed to operate at a high speed, in an efficient manner, which is also required of the inking devices, which inks the type or printing set up before each impression. The structure is such as to withstand heavy 75 usage, its durability is quite a factor for repairs are not always within the convenient command of the user, and is one of the reasons which led to the adoption of the present type of machine operating upon subsequently prepared gangs of tags, over the complicated types of machines, in which the tags or fasteners, and their application, were all formed and embodied within a single machine. 85

The printing instrumentalities adopted are such as universally meet the requirements for marking tags, and the printing set up may be produced in many available ways. 90

In the preferred embodiment, as disclosed herein, the type-holder or chase 7 is arranged for removably supporting type-bars in linear rows, lino-type or electros, which are inked during each downward 95 stroke of the actuator 2.

An inking-pad 8 is employed for inking the printing surface, which is moved into approximate parallelism with and yieldingly compressed against such printing surface as contradistinguished from any wiping or rubbing action across the type form or printing surfaces from one end toward another. The pad 8 is removably mounted upon a plate 9 projected from a knuckle member 10 floatingly fulcrumed upon the extremity of the lever 11. The end of the lever 11 is bifurcated with the knuckle member between the furcations, and yieldingly straddling a pin 12 fixed between 105 the furcations of the lever and engaged through a slot in the knuckle member, see 110

Fig. 4. A spring 13 is inserted within a bore in the knuckle member to position it between said member and pin. This floatingly fulcrums the knuckle member under tension in a radial direction away from the fulcrum pin 12 to yieldingly present the pad against the printing surface. The free end 14 of said knuckle member is notched so as to overlap the cross edge of the lever and thereby confine the hinge or swinging motion of the knuckle member, with a spring 15 inserted between the lever and a limb formed by said notch for normalizing the swinging or rocking motion of said knuckle member. The lever 11 is pivoted upon the arm 6 of the actuator so as to unitarily move therewith, and it is rocked by the cam lever 16, pivotally mounted upon a stationary support, and in this instance, between the ear bracket fixed to the table 6. The free end of the lever 16 is pivotally connected to a connecting link 17, which in turn is pivotally connected to the lever 11. The lever 16 is provided with a cam slot 18 within which a pin 19 traverses, fixed to and projecting from the actuator arm 6. The cam slot 18 is of such formation to intervally rock the lever 11 at the beginning or the printing stroke of the actuator to swing the pad into and out of engagement with the printing surface during such actuator stroke.

In the construction illustrated, the pad is moved to an inking position upon the return stroke of the actuator, which double inking, more thoroughly inks the printing surface and avoids complication in the actuating means, although it is obvious and within the aspect of this invention to divert the cam action so as to only be effective in one stroke of the actuator. A spring tension plunger 20 engages against the cam lever 16, stabilizing its movement and offers assistance in the lever movements.

Having described my invention, I claim:

1. In a device of the character disclosed, a printing press movable toward and from an impression surface, and inking mecha-

nism for inking the printing surface of said press, comprising an oscillating member unitarily combined with said press, an inking pad, a yielding floating knuckle pivotally connecting said pad to said oscillating member in a laterally extended direction, and means for oscillating said member. 55

2. In a device of the character disclosed, a printing press movable toward and from an impression surface, an inking pad movable against the printing surface of said press, an oscillating member, and a radially yielding floating knuckle member pivotally connecting said pad to said oscillating member, and capable of yieldingly compressing said pad against the printing surface of said press, and means operating through the movement of said press for actuating said oscillating member. 60

3. In a device of the character disclosed, a printing press movable toward and from an impression surface, an inking pad, means unitarily combined with said press for pivotally supporting said pad and moving the pad between the printing and impression surfaces of said press, and yieldingly compressing it against the printing surface, 75 during the printing movement of said press.

4. In a device of the character disclosed, comprising printing devices movable toward and from an impression surface, an inking pad therefor, lever means combined unitarily with said printing devices, and a coupling pivotally connecting said pad and lever means having its fulcrum yieldingly movable and its swing yieldingly confined, whereby the pad may be moved transversely 80 into approximate parallelism with the printing surface of said printing devices, and compressed against the same. 85

It witness whereof I hereunto subscribe my name, as attested by the two subscribing 90 witnesses.

FREDERICK KOHNLE.
